UNITED STATES PATENT OFFICE.

GEORGE H. FOLLOWS, OF CINCINNATI, OHIO, ASSIGNOR TO THE MILLER, DU BRUL & PETERS MANUFACTURING COMPANY, OF CINCINNATI, OHIO, A CORPORATION OF OHIO.

CIGAR-WRAPPER-CUTTING MACHINE.

SPECIFICATION forming part of Letters Patent No. 693,253, dated February 11, 1902.

Application filed June 8, 1901. Serial No. 63,761. (No model.)

To all whom it may concern:

Be it known that I, GEORGE H. FOLLOWS, a citizen of the United States, and a resident of Cincinnati, in the county of Hamilton and State of Ohio, have invented certain new and useful Improvements in Cigar-Wrapper-Cutting Machines, of which the following is a specification.

My invention relates to a machine having a cutting-platen upon which a leaf of tobacco is suitably held, as by air-suction, in position to have a wrapper cut therefrom by a coöperating roller swinging from side to side above the platen. Such machines have heretofore generally employed a cutting-die embedded in the table and a roller extending across the die and suitably mounted to swing from side to side and press the leaf into cutting contact with the edges of said die. It has also been proposed in United States Letters Patent of Albert Du Brul, No. 676,677, dated June 18, 1901, to provide a cutting-tool and what has been termed a "floating support" for the tool, by which it is permitted to have freedom of horizontal movement in any direction and rendered capable of traversing the outline of a wrapper, and a guide in which the tool works and by which it is directed in a path conforming in outline to the wrapper to be formed. This new system of floating and guiding the tool in a cigar-wrapper-cutting machine gave rise to a novel plan of operation invented by the aforesaid Albert Du Brul, in which the die in the table is dispensed with and the cutting is accomplished by a rotary cutter in the operating end of the tool traversing an unobstructed platen upon which the leaf is held by air-suction, the shape of the wrapper being secured by the guide directing the course of the cutter and the air-suction perforations being disposed so as to leave an uninterrupted cutting-path for the cutting-disk. For this type of machine United States Letters Patent No. 676,813 were granted June 18, 1901.

One feature of my present invention is applicable to both the aforesaid patent types of machines, and consists in certain means whereby the tool is caused to engage the guide at a plurality of points.

Another feature of my invention is applicable to that type of the above-described machines which employs an embedded die having a depressible platen within it, and consists in providing a pivoted platen-support to raise and rigidly hold the platen to the level of the cutting edge of the die to prevent the die cutting the fingers and to provide a rigid and smooth rolling-surface when the tool is removed from position over the platen to leave the table free for rolling the wrapper on the bunch, said means being constructed to depress the platen to expose the edge of the die when the tool is returned to operative position. The platen-support is preferably moved by a cam carried by the tool-mounting.

My invention will be readily understood upon reference to the accompanying drawings, in which—

Figures 1, 2, and 3 are respectively a side elevation of the machine, a plan of the tool and guide and their mounting, and a plan of the platen-support. Fig. 4 is a detail view of the coöperating tool, illustrated as having a roller pressing upon the edge of a die.

1 represents the cutting-table; 2, the die embedded therein; 3, the perforated depressible platen within the die, supported through guide-stems 4, working through openings 5 in suction-chamber 6. These parts are not new with me.

7 represents standards, in which is mounted a horizontal shaft 8, carrying a supporting-bracket 9, in the outer end of which is mounted a tool 10, that coöperates with the cutting-die to effect the cutting operation. The type of tool here shown has a roller 11 mounted on a horizontal axis in its lower end, made to traverse the edge of the die to press the leaf thereon. It is important that the roller or other form of operating end of the tool should remain at all times with its axis normal to the path in which it travels—that is to say, with the axis of the roller (or of the cutting-disk in types using such) transverse to the edge of the die or line of travel—and it is desirable to have the operating end in the vertical line of the tool's axis. This is accomplished by providing the guide 12 on the shaft 8 with a continuous groove conform-

ing in outline to the wrapper to be cut and having the tool engage therewith through the medium of a plurality of rollers or pins 13 on either side of or eccentrically disposed upon 5 its vertical shank 10^a, entering the groove and alined therein and prevent the tool from turning or twisting relatively thereto.

14 represents a forked supporting-lever fulcrumed at 15 beneath the table, the forward 10 ends of which being secured between knife-edge washers 16 and nuts 17 on the guide-stems 5 of the depressible platen 3. The supporting-lever 14 is rocked upon its fulcrum in the direction to raise the platen 3 by a cam 15 18 on shaft 8 acting against the upper end of a vertical pin 19 when the guide and tool are raised from operative position after cutting a wrapper, and the depressible platen is to be sustained rigidly during the rolling action; but when the cutting-tool and guide are returned to operative position cam 18 releases pin 19 and the depressible platen is free to return to its depressed position.

Having thus described my invention, the 25 following is what I claim as new therein and desire to secure by Letters Patent:

1. A machine for cutting out wrappers from tobacco-leaf, comprising an air-suction table; a tool coöperating with said table to cut out 30 the wrapper, supported above the table, having freedom of horizontal movement relatively to the table, also having a vertical axis of rotation upon which it turns in its support, and impinging the tobacco-leaf at a point in 35 the line of its said vertical axis; and a guide conforming to the outline of the wrapper to be cut, engaging the tool in the vertical line of its turning axis and positively directing its turning movement, as well as the direction of 40 its travel relatively to the table, and keeping its transverse axis at all times normal to the edge of the wrapper being cut.

2. A machine of the type described for cutting wrappers from tobacco-leaf, comprising 45 an air-suction table, a guide conforming to the wrapper to be cut, a tool-support having freedom of horizontal movement over the table, and a tool coöperating with the table to cut a leaf, having a rotary bearing in said 50 support and a non-rotating bearing in the guide; the bearing in the guide, the bearing in the support, and the point of impingement of the tool with the tobacco-leaf all being substantially in the vertical axis of the tool.

55 3. A cigar-wrapper-cutting machine embodying a cutting-table having means for holding a tobacco-leaf thereon by air-suction; a tool-support mounted to have freedom of horizontal movement over said table; a guide 60 supported above the table having a track conforming to the outline of the wrapper to be cut; a tool rotatable upon a vertical axis, on said tool-support, engaging the guide and caused to follow the same; a rotating part 65 mounted in the lower end of the tool upon a horizontal axis in the vertical line of the axis

upon which the tool rotates; and means carried by the said tool engaging the said track at a plurality of points in the line of travel; preventing the tool rotating upon its vertical 70 axis relatively to the track and keeping the horizontal axis normal to the path of travel.

4. In a cigar-wrapper-cutting machine, the combination of a cutting-table having air-suction means for holding a tobacco-leaf 75 thereto, a floating tool coöperating with said table to cut out a wrapper from said leaf having a rotary operating end in the vertical line of its axis, and means for defining the path of said floating tool, consisting of the guide 80 having a downwardly-presented groove conforming in outline to the wrapper to be cut, and a plurality of rollers or pins on the upper end of said tool entering the groove and alined therein and thereby preventing the tool from 85 turning on its vertical axis relatively to the groove in which it is confined, and holding the axis of its operating end normal to the path in which it travels.

5. In combination with a cigar-wrapper cutting and rolling table having a cutting-die, and a depressible platen within said die, a coöperating tool above the table, a movable tool-support upon which the tool is moved into and out of working position in relation to the platen and a support for said depressible platen, having connection with the movable tool-support through which it is moved to raise the platen and permit its depression as the tool moves away from and 95 into its operative position, whereby the platen 100 affords a rigid support when rolling the wrapper upon the bunch.

6. In combination with a cigar-wrapper cutting and rolling table, having a cutting-die and a depressible platen therein, a tool coöperating with the die to cut the wrapper and movable into operative position for cutting and out of such position to leave the table unobstructed for rolling, a supporting-lever for said platen fulcrumed beneath the table, and holding the platen rigid when rolling the wrapper, and a cam on the tool-support, moving said supporting-lever in the direction to raise the platen as the tool moves 115 out of operative position.

7. In a cigar-wrapper-cutting machine the combination of a table, a die having a depressible platen, a tool that coöperates with said die, a horizontal rock-shaft upon which the tool is mounted to swing vertically out of operative position, a supporting-lever for said platen fulcrumed beneath the table, a vertical thrust-rod on the end of said lever, and a cam on the horizontal shaft engaging the 125 thrust-rod as the tool rises, for the purpose set forth.
